UNITED STATES PATENT OFFICE.

ROBERT A. LORIG, OF MADISON, WISCONSIN, ASSIGNOR TO BURGESS BATTERY COMPANY, OF MADISON, WISCONSIN, A CORPORATION OF WISCONSIN.

DESIGN FOR BATTERY CABINET.

Application filed August 18, 1928. Serial No. 27,877. Term of patent 14 years.

To all whom it may concern:

Be it known that I, ROBERT A. LORIG, residing at 531 Winga St., city of Madison, county of Dane, and State of Wisconsin, a citizen of the United States, have invented a new, original, and ornamental Design for Battery Cabinet, of which the following is a specification, reference being had to the accompanying drawing, forming part thereof.

The figure is a perspective view of a battery cabinet showing my new design.

I claim:

The ornamental design for battery cabinet, as shown.

ROBERT A. LORIG.
